ANTENNA INSULATOR

Stanley B. Valiulis, Rockford, Ill.

Application February 11, 1954, Serial No. 28,967

Term of patent 14 years

(Cl. D26—14)

Fig. 1 is a perspective view showing my new design for an antenna insulator, indicating in dotted lines adjacent portions of an antenna assembly for the purposes of illustration only;

Fig. 2 is a top view;

Fig. 3 is a front view, and

Fig. 4 is a side view.

I claim:

The ornamental design for an antenna insulator, substantially as shown and described.
